E. J. WITCHGER

CASE FOR A TAPE MEASURE

Filed Nov. 8, 1926

Eugene J. Witchger
INVENTOR.
BY
George B. Willcox
ATTORNEY.

UNITED STATES PATENT OFFICE.

EUGENE J. WITCHGER, OF SAGINAW, MICHIGAN, ASSIGNOR TO LUFKIN RULE CO., OF SAGINAW, MICHIGAN, A CORPORATION OF MICHIGAN.

DESIGN FOR A CASE FOR A TAPE MEASURE.

Application filed November 8, 1926. Serial No. 19,641. Term of patent 14 years.

To all whom it may concern:

Be it known that I, EUGENE J. WITCHGER, a citizen of the United States, residing at Saginaw, in the county of Saginaw, State of Michigan, have invented a new, original, and ornamental Design for a Case for a Tape Measure, of which the following is a specification, reference being had to the accompanying drawing, forming part thereof.

The drawing is a perspective view of the article showing my new design.

I claim:

The ornamental design for a case for a tape measure as shown.

EUGENE J. WITCHGER.
